CLAIM

The ornamental design for an electronic rodent trap, as shown and described.

DESCRIPTION

FIG. 1 is a rear, top and left side perspective view of an electronic rodent trap, according to the present design;

FIG. 2 is a front, top and left side perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front elevation view thereof;

FIG. 8 is a rear elevation view thereof;

FIG. 9 is a perspective view of the top detached section of electronic rodent trap of FIG. 1; and,

FIG. 10 is a rear view of the top detached portion of electronic rodent trap of FIG. 1.
